UNITED STATES PATENT OFFICE.

HEINRICH FREESE, OF BERLIN, GERMANY.

WOOD PAVEMENT.

SPECIFICATION forming part of Letters Patent No. 595,616, dated December 14, 1897.

Application filed March 25, 1897. Serial No. 629,222. (No model.)

To all whom it may concern:

Be it known that I, HEINRICH FREESE, a subject of the Emperor of Germany, residing at 18 Rungestrasse, in the city of Berlin, Germany, have invented certain new and useful Improvements in Wood Pavements; and I do hereby declare the following to be a full, clear, and exact description of the invention, such as will enable others skilled in the art to which it appertains to make and use the same.

In constructing wood pavements heretofore the great difference in the character of the wood blocks has not been taken into consideration. It is decidedly of the utmost importance for the durability of the pavement whether the wood employed comes from the top or butt end of the tree or whether it is from the hard or from the outer softer parts of the trunk. The same log will have a much greater resisting power when its individual properties are considered systematically or are made use of as in the wood pavement described hereinafter. In wood pavements it is important to allow rain to penetrate as little as possible, and therefore each log should be so placed that always the top end of the wood is placed upwardly and the butt-end downwardly.

Figure 1 of the accompanying drawings shows a piece of plank from which the paving-blocks are cut.

a is the top end; *b*, the butt-end.

Fig. 2 shows a block as it should be placed in the street, and Fig. 3 shows a block as it should not be placed. Fig. 4 is a plan view of a street so paved as to present the hard side of the blocks in the direction of traffic, and Fig. 5 is a plan view of a street having the blocks set in diagonal direction.

The sap or vital juice in a tree is naturally passing from below toward the top. In impregnating wood the liquids employed follow in the same direction as the sap in the living wood—*i. e.*, they also penetrate from the base to the top. It is extremely difficult for liquids to penetrate in the opposite direction, from above downwardly. Now for wood paving, in view of the importance that rain-water should penetrate into the blocks as little as possible, it is preferable to place all the blocks in the same manner as a tree growing in a forest—that is to say, the top end facing up-

wardly. The rain-water will then penetrate less into the wood than if the blocks were placed up or down, just as they happened to pass the hands of the paver. Of the same importance, as in the tree, the top or butt end is the hard side and the softer side of the sap-wood. In paving this must be taken into consideration. The blocks must be carefully sorted, for the hard side of each block has much more resisting force than the sap side, and thus in placing the blocks each should be so positioned as to present the hard side in the direction where the strongest effort from horses' hoofs and from wagons may be expected.

Fig. 4 is a plan view of the street with the pavement executed in this manner. The line *c d* is the middle line of the street. On both sides of the lines *c d* the arrows indicate the line of traffic. In order to bring the hoofs of horses as much as possible in contact only with the hard side, the blocks are also arranged that the heart is placed in the direction of the traffic. The durability of the pavement is thereby greatly increased and the pavement lasts much longer than a pavement wherein the soft sides are exposed to horses' hoofs or in a pavement wherein heart and sap are employed indiscriminately with little or no system.

Fig. 5 is a plan view of a street having the blocks set in diagonal direction. When a street is very steep, the blocks are preferably placed on both sides of the middle line *c d*, turning the heart side in the same direction and uphill. This is evident as being best for wagons and carts going upwardly and for loaded vehicles coming down the street. The hoofs of the horses can attack the blocks at the edge also pointing uphill, in taking up the load of the wagons being only partially braked.

Wood pavements in which the character of the wood has been considered in the described manner wear out much more evenly and slowly than pavements wherein the blocks have been set without any system.

Having thus described my invention, I claim—

A wood pavement composed of blocks placed on end having the fiber running in a vertical direction and having the butt-end of

the tree on the base of the street and the top
end of the tree directed upwardly and hav-
ing the heart side of the wood pointed in the
direction from which the hoofs of horses are
5 liable to attack the pavement, substantially
as described.

In witness whereof I have hereunto signed

my name in the presence of two subscribing
witnesses:

HEINRICH FREESE.
